Primary Examiner — Robin V Webster

CLAIM

The ornamental design for a container for a fluid dispensing device, substantially as shown and described.

DESCRIPTION

FIG. 1 is an isometric view of a container according to one embodiment of the present invention, viewed from above, in front of, and from the right side of the container; FIG. 2 is a front elevation view of the container of FIG. 1; and, FIG. 3 is a top plan view of the container of FIG. 1. The broken lines represent environmental structure and form no part of the claimed design.

1 Claim, 3 Drawing Sheets
